DESIGN FOR A LAMP

Herbert Rubin, New York, N. Y.

Application Jan. 17, 1946, Serial No. 125,650

Term of patent 14 years

(Cl. D48—20)

To all whom it may concern:

Be it known that I, Herbert Rubin, a citizen of the United States of America, residing at New York, in the county of New York and State of New York, have invented a new, original, and ornamental Design for a Lamp, of which the following is a specification, reference being had to the accompanying drawing, forming part thereof.

Figure 1 is a front elevation of a lamp showing my new design.

Figure 2 is a side elevation at right angles to the showing of Figure 1.

Figure 3 is a section taken on line 3—3 of Figure 1 looking in the direction of the arrows, and

Figure 4 is a bottom plan view of the base of the lamp within the confines of the arrows 4—4 in Figure 2.

I claim:

The ornamental design for a lamp, as shown.
HERBERT RUBIN.
